UNITED STATES PATENT OFFICE.

CHARLES P. STEINMETZ, OF SCHENECTADY, NEW YORK, ASSIGNOR TO GENERAL ELECTRIC COMPANY, A CORPORATION OF NEW YORK.

ELECTRICAL WINDING.

1,194,090.

specification of Letters Patent. Patented Aug. 8, 1916.

Application filed November 27, 1914. Serial No. 874,168.

To all whom it may concern:

Be it known that I, CHARLES P. STEINMETZ, a citizen of the United States, residing at Schenectady, in the county of Schenectady, State of New York, have invented certain new and useful Improvements in Electrical Windings, of which the following is a specification.

My invention relates to electrical windings for substantially all kinds of electrical apparatus, but particularly to those for transformers.

The object of my invention is to so arrange the coils of electrical windings that abnormal frequencies may not build up disastrously high voltages in resonating groups thereof.

My invention from one aspect is an improvement in an embodiment of the invention of Elmer E. F. Creighton, disclosed in his application, Serial No. 874,068, filed on or about Nov. 25, 1914.

As has been recognized prior to my invention, abnormally high frequencies may give rise to disastrously high voltages within an electrical winding, if there happens to be accessible to the high frequency a section of the winding whose natural frequency, or a harmonic thereof, is equal to the ab- normal frequency. The value of the voltage developed by a given application of a resonating frequency, is dependent upon the value of the energy in the resonating section of the winding, and hence resonance in one or more of the groups into which it is generally necessary to assemble the coils of a large winding, is particularly dangerous since the amount of energy therein is necessarily great.

My invention is to protect windings against the dangers of resonating groups of coils. Broadly, I provide the different, or at least adjacent, groups of coils with such different natural frequencies that the frequency at which one group oscillates can not readily pass over other groups.

In carrying out my invention I assemble the coils of a winding into groups as heretofore, but with unequal numbers of coils per group instead of equal numbers of coils per group, as has been the common practice. The coils may be similar in all respects to those now employed, in which case my invention may be embodied in new apparatus at substantially no increase in the cost of

manufacture thereof. The coils of any one group may or may not all be alike, whence the groups may or may not contain equal numbers of turns per group as other conditions may dictate, but in case they are given equal numbers of turns, care must be taken that the tendency to change the frequency of the groups, due to the different numbers of coils per group, is not overcome by the necessary differences between the coils. The tendency of different numbers of coils per group to bring about materially different natural periods for the groups is, however, so great that there is little likelihood of its being effectively neutralized by the differences between the coils.

Preferably each two adjacent groups are composed of different numbers of coils. This arrangement, whereby each two adjacent groups have materially different natural periods, provides for damping or restraining by interference the oscillation of each group, whether the resonating frequency is produced therein or transmitted thereto over another group by a continued application of the frequency from outside the resonating group. Preferably also each end or terminal group is composed of a different, generally smaller, number of coils than are the respective inner groups. This latter arrangement whereby the outer groups have higher natural frequencies than the inner groups, serves best to prevent or restrain the entrance of abnormal frequencies to the inner coils from outside the winding, where the greatest number of abnormal frequency disturbances arise. The outer groups may be more heavily insulated than the others, if necessary, since they are immediately accessible to resonating frequencies produced outside the apparatus.

In the accompanying drawing, which forms a part of this specification, I have illustrated diagrammatically in elevation, a shell type transformer embodying my invention.

My invention is here shown embodied in the high voltage winding only, but it will be understood that it is not thus limited. The middle leg of the core 1 carries the windings. The low voltage winding is made up of seven separate coils 2—8. The high voltage winding is made up of thirty-six separate coils assembled into six groups intermixed with the coils of the low voltage

winding, each group being between two low voltage coils. The coils of each winding are connected in series. The first group A of the high voltage winding comprises four 5 coils, the second B and fourth D six coils each, the third C eight coils, and the fifth group E and the sixth group F seven and five coils respectively. The coils may or may not be made up of equal numbers of 10 turns and thus the groups may or may not comprise unequal numbers of turns. Each two adjacent groups have different natural frequencies and the two terminal groups have higher natural frequencies than the 15 inner groups.

While I have described the principle of my invention, and the best mode I have contemplated for applying its principle other modifications will occur to those skilled in 20 this art and I aim in the appended claims to cover all modifications which do not involve a departure from the spirit and scope of my invention.

What I claim as new and desire to secure 25 by Letters Patent of the United States, is:—

1. An electrical winding comprising a plurality of coils assembled in groups, the adjacent groups thereof comprising different

numbers of coils to restrain the building up of dangerously high voltages through resonance. 30

2. An electrical winding comprising a plurality of coils assembled in groups, said groups having different numbers of coils to restrain the building up of dangerously high 35 voltages through resonance.

3. An electrical winding comprising a plurality of coils connected in series and assembled in more than two groups, each of the two terminal groups comprising a different 40 number of coils than the inner groups to restrain the building up of dangerously high voltages through resonance.

4. In a transformer, a winding comprising a plurality of electrically connected coils 45 assembled in groups and a second winding separating the said groups, adjacent groups comprising unequal numbers of coils respectively, to restrain the building up of dangerously high voltages through resonance. 50

In witness whereof, I have hereunto set my hand this 24th day of November, 1914.

CHARLES P. STEINMETZ.
